RECEPTACLE FILLING APPARATUS

Peter Aberman, Caldwell, Idaho

Application July 1, 1946, Serial No. 630,666

6 Claims. (Cl. 226—2)

1

This invention relates to an apparatus for feeding small articles or products, or granular or like materials, to receptacles, preparatory to placing them in a treating chamber.

In ordinary or prior apparatus of this kind, the quantity of articles, products, or materials fed to the receptacles varies according to the rate of supply thereof to the receptacles as they are moved along at a uniform speed by conveying means. As a result of this, the articles, products, or materials are not properly or uniformly treated, the treatment being excessive when the quantity is greater. The outcome is, therefore, a non-uniform and unsatisfactory product of the treatment.

The primary object of the present invention, therefore, is to provide an apparatus of the above kind embodying novel and efficient means to automatically speed up and slacken the movement of the receptacle conveying means in accordance with the volume of the articles, products, or materials delivered to the receptacles, whereby to secure beds of uniform thickness of such articles, products, or material in the receptacles and thereby insure uniform and satisfactory treatment of the articles, etc.

While the present invention is primarily designed for use in filling trays with foods and other articles, products and materials for drying, it is equally adaptable for use where the treatment is other than drying.

The invention contemplates the provision of a feed conveyor for the receptacle filling means which is tiltable about a horizontal axis and which is loaded by weight or spring to normally swing upwardly and to swing upwardly or downwardly in accordance with the volume of the articles, products or materials delivered thereto. The receptacle conveying means is driven by a motor through a variable speed transmission device having a speed control mechanism which includes a lead screw rotatable in one direction to increase the speed of the conveying means and in the opposite direction to decrease the speed thereof. Reversible driving means is provided for the lead screw which has a reversing device connected and responsive to the tilting movements of the feed conveyor.

The invention further contemplates a receptacle conveying means including conveyor belts, and trays adapted to be placed on said conveyor belts to receive the articles, products or material to be treated. The feed conveyor discharges into a feed hopper which delivers into the trays and has a bottom outlet provided with a movable clo-

2

sure gate, means being provided for automatically closing the gate when the vertical transverse walls of the trays register with the hopper outlet, so as to prevent delivery onto said walls and to automatically open the gate when said walls move out of registry with the hopper outlet so as to permit deposition of the articles, products, or material in beds of uniform thickness within said trays.

10 The articles, products, or materials are delivered to the feed conveyor by means including an endless belt conveyor, and are spread in an even bed on the latter by a vertically movable spreader. Means is provided to automatically raise and lower the spreader in accordance with the volume of articles or the like delivered to said endless belt conveyor from the variable source of supply, such means being operatively connected to a reversible shaft of the reversible driving means for 20 the lead screw of the transmission device control mechanism.

The exact nature of the present invention, as well as more specific objects and features thereof, will become apparent from the following description when considered in connection with the accompanying drawings in which—

Figure 1 is a side elevational view of an apparatus constructed in accordance with the present invention,

30 Figure 2 is a central longitudinal sectional view thereof,

Figure 3 is a view similar to Figure 1 looking at the opposite side of the apparatus,

Figure 4 is a vertical transverse section taken 35 on line 4—4 of Figure 2,

Figure 5 is a vertical transverse section taken on line 5—5 of Figure 2,

Figure 6 is a horizontal section taken on line 6—6 of Figure 2,

40 Figure 7 is a horizontal section taken on line 7—7 of Figure 2,

Figure 8 is a fragmentary longitudinal section showing the gate of the hopper open as allowed when the transverse walls of the trays move out 45 of registry with the outlet of the hopper from the position of Figure 2,

Figure 9 is a view similar to Figure 1 illustrating a modification of the apparatus,

Figure 10 is a fragmentary end view looking toward the right of Figure 9 so as to more clearly reveal details of the modification, and

50 Figure 11 is a wiring diagram illustrating the manner in which the reversing switch controls the reversible motor, of the modification shown in Figures 9 and 10, by which the lead screw of

the speed control mechanism for the variable speed transmission is driven.

Referring in detail to the drawings, 5 indicates a suitable frame having journaled transversely of and within the upper portion thereof one end roller 6 of an endless conveyor belt 7 that leads from the source of supply of the articles, products or materials to be treated. The articles, products, or materials are delivered in varying volume from the source of supply by the conveyor belt 7. An intermediate belt conveyor 8 is provided in the upper portion of frame 5 to receive the material or the like discharged from the belt 7, which conveyor 8 is driven by a suitable motor 9 mounted on the frame 5. Pivotally mounted at one end within the frame 5, as at 10, is a spreader frame 11 that is arranged directly over the conveyor 8 and has a V-shaped spreader 12 fixed therein with its pointed end directed toward the receiving end of the conveyor 8. The spreader 12 spreads the material in an even layer on the belt of conveyor 8 for substantially the full width thereof, the thickness of the bed of material depending upon the distance to which the spreader is adjusted from the upper flight of the belt of conveyor 8. Means is provided for automatically swinging the frame 11 so as to adjust the spreader 12 relative to the belt of conveyor 8 in accordance with the volume of material discharged thereon, as will be later described.

A relatively short feed conveyor of the endless belt type, indicated at 13, is mounted directly beneath the discharge end of conveyor 8 to receive the material or the like from the latter. The frame of conveyor 13 is pivotally mounted at one end, as at 14, so as to be tilttable about a horizontal axis, and the frame of this conveyor has an arm 15 which is rigid therewith and projects beyond the pivot 14. A weight 16 is slideable on the arm 15 so as to adjustably counterbalance the conveyor 13 when a predetermined volume of material or the like is delivered to the latter. It will thus be apparent that the conveyor 13 will rise and fall or swing upwardly and downwardly about the pivot 14 in accordance with the volume of material or the like delivered thereto.

The feed conveyor 13 discharges into a hopper 17 mounted in the frame 5 directly below the discharge end of conveyor 13, and which has a bottom outlet provided with a movable closure gate 18. From the hopper 17 the material or the like is discharged into trays 19 which are carried past the hopper by means of a conveying means including spaced conveyor belts 21. This conveying means extends from a source of supply of the trays, and the trays are placed on the belts 21 in end-to-end relation as shown.

Means is provided for automatically closing the gate 18 when the vertical transverse walls of the trays 19 are in registry with the outlet of hopper 17 so as to prevent delivery of the material or the like onto said walls, and to automatically open the gate when said walls move out of registry with the hopper outlet, so as to permit discharge of the material or the like in beds of uniform thickness within said trays. This means may consist of a lever 22 secured on a rock shaft 23, mounted in front of the hopper 17 and provided with depending arms 23', each having a roller 24 at its lower end arranged to ride across the transverse walls of the trays. A flexible member 25 is attached to the upper end of lever 22 and passes rearwardly around an idler pulley or guide 26. From the guide 26, the flexible member 25 passes around and is attached to a fur-

ther pulley 27 secured on the shaft of gate 18. The arrangement is such that when the rollers 24 pass into a tray, the lever 22 is allowed to swing in a direction to provide slack in the flexible member 25 so that the gate 18 may swing downwardly to open position by gravity. The arrangement is also such that when the rollers 24 ride onto the transverse walls of the trays 19, the lever 22 is swung in a direction to exert a pull on the flexible member 25 and thereby cause the gate 18 to swing upwardly to closed position. The arms 23' of shaft 23 are sufficiently heavy to cause the lever 22 to normally swing in a direction to provide slack in flexible member 25.

At the discharge end of the conveying means, the belts 21 thereof pass around rollers 28 secured on a transverse shaft 29 which is operatively connected by a chain gearing at 29 with the driven shaft 30 of a variable speed transmission device 31 which is preferably of the type disclosed in the U. S. patent to G. T. Pfeifer, 2,189,294, dated February 6, 1940. As disclosed in said patent, the transmission device 31 is provided with a driving motor 32 which is in driving relation with an adjustable pulley structure which, by means of a belt, drives another adjustable pulley structure mounted on the driven shaft 30. Also the transmission device 31 has a speed control mechanism that includes a lead screw as indicated at 33, which is rotatable in one direction to increase the speed of the driven shaft 30 and the conveying means driven thereby, and in the opposite direction to decrease the speed thereof.

Reversible driving means is provided for the lead screw 33 which has a reversing device connected and responsive to the tilting movements of the feed conveyor 13. In the embodiment of Figures 1 to 8, inclusive, this reversible driving means includes a transverse driven shaft 34 operatively connected by a chain or like gearing 35 and a spur gearing 36 with the lead screw 33. The reversing device includes two frames 37 and 38 loosely mounted on the shaft 34 intermediate their ends for rocking movement, each of said frames having an idler pulley 39 at one end and a drive pulley 40 at the other end which is secured upon a drive shaft 41. The pulleys 39 and 40 of frame 37 are located directly above the return strand of one of the belts 21, while the pulleys 39 and 40 of the frame 38 are located directly beneath said strand. Also, the pulley 40 of frame 37 is located at one side of the shaft 34, while the pulley 40 of the other frame is located at the opposite side of said shaft. Each driven pulley 40 is operatively connected by a belt or other non-positive gearing 42 with the shaft 34. The arrangement is such that when corresponding ends of the frames 37 and 38 are moved toward each other the idler pulley 39 of frame 37 and the drive pulley 40 of frame 38 are brought into engagement with the adjacent belt 21 so that said pulley 40 of frame 38 is driven thereby in one direction, the idler pulley 39 of frame 38 and the drive pulley 40 of frame 37 being simultaneously moved away from and out of engagement with said belt. The arrangement is also such that when said corresponding ends of the frames 37 and 38 are moved apart the idler pulley 39 of frame 38 and the drive pulley 40 of frame 37 are moved into engagement with the belt 21, while the idler pulley 39 of frame 37 and the drive pulley 40 of frame 38 are simultaneously moved out of engagement with the belt 21. The engagement of the drive pulley 40 of frame

37 with belt 21 causes shaft 34 to be driven in the opposite direction, and it will thus be seen that the lead screw 33 may be turned in opposite directions to automatically speed up and slacken the movement of the conveying belts 21. In order to automatically speed up and slacken the movement of the conveying belts 21 in accordance with the volume of the articles or the like delivered to the feed conveyor 13, the frame of the latter is operatively connected to corresponding ends of the frames 37 and 38 by means of an adjustable link 43, a bell crank lever 44, and toggle links 45, as more clearly shown in Figure 1. The arrangement is such that when the feed conveyor 13 is over-balanced to swing downwardly by the material delivered thereto and against the action of weight 16, the ends of the frames 37 and 38 to which the toggle links 45 are connected will be drawn together so as to engage the drive pulley 40 of frame 38 with the adjacent belt 21. Motion is transmitted from this engaged pulley 40 to the lead screw 33 through the gearing described, whereby to rotate said lead screw in the proper direction to cause the belts 21 to be speeded up. The arrangement is also such that when the supply of material or the like to the feed conveyor 13 is diminished to an extent which allows the weight 16 to swing the conveyor 13 upwardly, the ends of the frames 37 and 38 to which the toggle links 45 are connected will be spread apart and the drive pulley 40 of frame 37 will be engaged with the adjacent belt 21. As the drive pulleys 40 are at opposite sides or faces of the adjacent belt 21, it will be apparent that the engagement of pulley 40 of frame 37 with the belt 21 will cause the lead screw 33 to be turned in the opposite direction for slackening the movement of the belts 21. The conveying means which carries the trays past the hopper is thus automatically speeded up and slackened in speed in accordance with the volume of the material or the like delivered to the feed conveyor 13. In this way, the material or the like is discharged into the trays 19 so as to secure beds of the material or the like in such trays which are of uniform thickness. Thus, the material or the like will receive a uniform and satisfactory treatment.

The conveying belt 21 with which the reversing device is associated has its lower or return strand passed about superposed guide pulleys 46 and 47, the latter of which is secured upon a transverse shaft 48 journaled in the frame 5. The shaft 48 is thus driven by the belt 21 referred to, and motion is transmitted from the pulley 47 to a shaft of the conveyor 13 by means of belt or like gearings 49 and 50.

Means is provided, as hereinbefore mentioned, for automatically raising and lowering the spreader 12 in accordance with the volume of material delivered to the belt conveyor 8, thereby providing for proper elevation of the spreader 12 in accordance with the thickness of the bed of material to be spread thereby on the belt of said conveyor 8. This means includes a small winding drum 51 secured on a transverse shaft 52 journaled in the frame 5 above the spreader 12 and its frame 11. One end of a flexible member 53 is attached to the drum 51, and the other end thereof is secured to the free end of the frame 11, as at 54. Shaft 52 carries a pulley 55, around which passes a driving belt 56 that also passes around another pulley 57 secured on the reversible shaft 34. The arrangement is such that, as the shaft 34 is driven in one direction

to speed up the conveying belts 21, shaft 52 is driven so as to wind the flexible member 53 on drum 51 and thereby elevate the frame 11 and the spreader 12 carried thereby. The arrangement is also such that when shaft 34 is driven in the opposite direction to slacken the speed of the belts 21, drum 51 is rotated in a direction to unwind the flexible member 53 and allow the frame 11 and its spreader 12 to lower. The pulley on shaft 34 which receives the belts at 42 may drive said shaft 34 through a slip-clutch, so that excessive turning of lead screw 33 and drum 51 is prevented. It will be understood that the conveying belts 21 are speeded up when the supply of material or the like to feed conveyor 13 increases. It follows, therefore, that at this time the volume of material deposited on conveyor 8 is increased and that the spreader 12 should be raised at such time as has been explained. Conversely, conveying belts 21 are slackened in speed when the volume of material or the like delivered to the conveyor 13 is diminished. For this reason, the material delivered to conveyor 8 will also be diminished and the spreader 12 should be and is lowered to properly spread the thinner layer of material on the belt of conveyor 8 as has been explained.

In the embodiment of Figures 9 to 11, inclusive, a reversible electric motor 58 is provided for directly driving the lead screw 33 of the transmission device 31 through a slip clutch, in lieu of the reversible driving mechanism of Figures 1 to 8, inclusive. This motor 58 is controlled by a reversing switch 59 having an operating lever 60 connected by a link 61 with the frame of the conveyor 13. The arrangement is such that when the volume of material or the like deposited on the conveyor 13 is sufficiently increased to cause said conveyor 13 to swing downwardly against the action of weight 16, switch 59 is operated to cause motor 58 to turn lead screw 33 in proper direction for causing the conveying belts 21 to be speeded up. The arrangement is also such that when the conveyor 13 and the material fed thereto is overbalanced by the weight 16 and the conveyor 13 swings upwardly due to diminished supply of material or the like to said conveyor 13, the switch 59 will cause the motor 58 to be reversed. This reversal of motor 58 will cause rotation of lead screw 33 in the opposite direction so that the conveying belts 21 are slackened in speed. Any suitable safety slip clutch may be provided at 62 between the shaft of motor 58 and the lead screw 33 so that motor 58 may continue to operate after turning lead screw 33 to its limit of movement in either direction, without damage to the lead screw 33 or parts actuated thereby.

In the embodiment of Figures 9 to 11, inclusive, the belts 56' and 57' for operating the drum 51 may be driven by a belt gearing 63 from the shaft of motor 58 as shown in Figure 10. Otherwise, the embodiment of Figure 9 to 11, inclusive, corresponds to that of Figures 1 to 8, inclusive, and remaining parts of both forms correspond and are indicated by similar reference characters.

The operation of the various elements and mechanisms has been explained during description of the construction, and it is accordingly believed that the operation will be clearly understood by those skilled in the art without further explanation. Minor changes in structural details and further modifications are contemplated such as fall within the scope of the invention as claimed. It will be seen that the invention relates

to an apparatus wherein the speed of movement of the trays past the hopper varies in accordance with the volume of material fed to the trays.

What I claim is:

1. In an apparatus of the character described, the combination of an endless belt-conveying means for continuously carrying receptacles past a feed hopper, means for continuously delivering articles or the like to said feed hopper including a feed conveyor tiltable about a horizontal axis, yieldable means acting to normally swing said feed conveyor upwardly, driving means for said conveying means including a motor-driven variable speed transmission device having a speed control mechanism including a lead screw rotatable in opposite directions to vary the speed of said conveying means, and reversible driving means for said lead screw connected and responsive to the tilting movements of said feed conveyor for rotating the lead screw in a direction to slacken the speed of the conveying means when the feed conveyor is swung upwardly by said yieldable means and for rotating the lead screw in the opposite direction to increase the speed of said conveying means when the feed conveyor is swung downwardly against the action of said yieldable means by the articles or the like supplied to the feed conveyor.

2. The construction defined in claim 1, wherein in said reversible driving means includes a driven shaft geared to said lead screw, drive pulleys mounted above and below a belt of said conveying means for independent movement toward and away from said belt, similar non-positive driving connections between said pulleys and said driven shaft, and means connecting the feed conveyor to said pulleys for moving one of the pulleys into engagement with said belt and the other pulley out of engagement therewith when the feed conveyor is swung upwardly and for moving said one pulley out of engagement with said belt and the other pulley into engagement therewith when the feed conveyor is swung downwardly.

3. The construction defined in claim 1, in combination with a hopper arranged to receive the articles or the like from said feed conveyor and to discharge the same into the receptacles placed

on said conveying means, a normally open closure gate for the outlet of said hopper, and means operable by transverse vertical walls of said receptacles for closing said closure gate when said walls are registered with the hopper outlet and for permitting opening thereof when said walls move out of registry with said outlet.

4. The construction defined in claim 1, in combination with an endless belt supply conveyor for delivering the articles or the like to the feed conveyor, a vertically movable spreader for evenly spreading the articles or the like on said endless belt supply conveyor, and means operated by said reversible driving means for raising said spreader when the conveying means is speeded up and for lowering the same when the speed of said conveying means is slackened.

5. In an apparatus of the character described, the combination of endless belt receptacle conveying means, means for continuously delivering articles or the like to said conveying means including a feed conveyor tiltable about a horizontal axis, yieldable means acting to normally swing said feed conveyor upwardly, driving means for said conveying means including a motor-driven variable speed transmission device having a speed control mechanism including a lead screw rotatable in opposite directions to vary the speed of said conveying means, and a reversible driving motor for said lead screw connected and responsive to the tilting movements of said feed conveyor for rotating the lead screw in a direction to slacken the speed of the conveying means when the feed conveyor is swung upwardly by said yieldable means and for rotating the lead screw in the opposite direction to increase the speed of said conveying means when the feed conveyor is swung downwardly against the action of said yieldable means by the articles or the like supplied to the feed conveyor.

6. The construction defined in claim 5, in combination with a reversing switch controlling the driving motor of said lead screw, and an operating connection between said reversing switch and said feed conveyor.

PETER AUBERMAN.
